ELECTRIC GLOW CANDLE

George W. Strayline, Dobbs Ferry, N. Y.

Application February 24, 1947, Serial No. 137,117

Term of patent 7 years

(Cl. D48—2)

To all whom it may concern:

Be it known that I, George W. Strayline, a citizen of the United States and a resident of Dobbs Ferry, county of Westchester, and State of New York, have invented a new, original, and ornamental Design for Electric Glow Candle, of which the following is a specification, reference being had to the accompanying drawings, forming part thereof and in which

Fig. 1 is a top plan view of an electric glow candle, showing my new design, and,

Fig. 2 is a side elevational view thereof.

I claim:

The ornamental design for an electric glow candle, substantially as shown.

GEORGE W. STRAYLINE.
